Inventor,
Ransom S. Potter

UNITED STATES PATENT OFFICE.

RANSOM S. POTTER, OF CHICAGO, ILLINOIS.

RAIL-SPlicing CHAIR.

Specification of Letters Patent No. 23,493, dated April 5, 1859.

To all whom it may concern:

Be it known that I, RANSOM S. POTTER, of the city of Chicago, in the county of Cook and State of Illinois, have invented a new and Improved Rail-Splicing Chair; and I do hereby declare that the following is a full, clear, and exact description of the construction and operation of the same, reference being had to the annexed drawings, 10 making a part of this specification, in which—

Figure A represents a side view of chair. Fig. B view of upper side of chair showing clamp put on. Fig. C end view of chair. Fig. D view of upper side of chair showing clamp removed. Fig. E view of under side of chair. Fig. F view of upper side of clamp the parts being represented by Figs. N, g. Fig. G, end view of clamp. 20 Fig. 2 shows the edge of plate turned over against neck of rail 8; 3 the neck of rail; 4 guard or fence to hold clamp 5; 5 clamp of a wedge like form; 6 inclined edge of the guard or fence; 7, 7, bolts; 8, 8, flange of rail, these figures having reference to all the different views presented in the annexed drawings.

The nature of my invention consists in so constructing a rail splicing chair that rails used in the construction of railroad tracks 30 will be held firmly and securely in place and present on their upper and inner surfaces even and smooth lines, by means of a clamp wedge fitted on the back to a guard or inclined projection on the outer lip of the chair which commences near the bolt holes, and as it rises recedes from the perpendicular at an angle of about twenty-two degrees. The back of the clamp wedge is made at the 40 same angle and on its inner and lower surfaces fitted to the flange or web of the rail and the neck, having on these parts the center at the point of rails slightly cut away to accommodate any inequalities which may 45 exist in the rails. The clamp wedge is then drawn down into place by means of ordinary bolts and as it is drawn down the same bolts operate the wedge and the clamp and a combined action is produced which 50 gives a pressure in three directions, while each end of the clamp wedge in a measure

acts separately upon its own rail; thus forming a chair easily applied and adjusted, strong and perfectly safe and one which can be used either on ties or between them, but 55 more advantageously between them it being designed for that purpose.

To enable others skilled in the art to make and use my invention I will proceed to describe its construction and operation. 60

I construct my rail splicing chair by using a wrought or cast iron plate with the inside edge turned over against the neck of the rail as shown at 2, 3, and 8 in Fig. C, of the accompanying drawings, thus forming 65 a recess or cavity, which is entirely filled up by the flange 8, and part of the neck of the rail as shown at 3. The outside edge of the chair is so elevated as to form a fence or guard between which and the rail is inserted a clamp 5, which fills the space the entire length of the chair and forms in connection with the chair the cavity for the outside flange of the rail. The inner face of the guard 6 is inclined from a vertical or 70 perpendicular line from without inward and the outer face of the clamp 5 is beveled so as to coincide with the face of the guard. The clamp is drawn to its place by two bolts 7, 7, passing through it and the bed of the 80 chair in which the holes for their reception are cut away transversely, converging from the top to the bottom, in order to allow the bolts to operate the wedge feature of the clamp; thus producing a vertical pressure 85 upon the flange of the rail 8, while the inclined face of the guard carries the clamp against the neck of the rail, as it is drawn down by the bolts.

I do not claim broadly a clamp wedge, nor 90 the form of the chair, but

What I do claim and desire to secure by Letters Patent is—

A clamp wedge operated by the same bolts as a clamp and as a wedge acting 95 upon each rail equally; in combination with the chair guard 6, substantially as shown and specified.

RANSOM S. POTTER.
